UNITED STATES PATENT OFFICE

FRANCIS N. WOODMAN, OF CLINTON, MASSACHUSETTS, ASSIGNOR TO WICKWIRE,
SPENCER STEEL COMPANY, OF NEW YORK, N. Y., A CORPORATION OF DELAWARE

DESIGN FOR A RADIATOR CABINET

Application filed January 7, 1930. Serial No. 34,044. Term of patent 7 years.

To all whom it may concern:

Be it known that FRANCIS N. WOODMAN, a citizen of the United States, residing at Clinton, in the county of Worcester and State of Massachusetts, has invented a new, original, and ornamental Design for Radiator Cabinet, of which the following is a specification, reference being had to the accompanying drawing, forming part thereof.

The figure is a perspective view of a radiator cabinet showing my new design, the ornamentation being continued throughout the center panel.

I claim:

The ornamental design for a radiator cabinet as shown and described.

FRANCIS N. WOODMAN.
